BINDER TYPE RECORD HOLDER

John Wesley Schroeder, Monterey Park, Calif.

Application May 17, 1955, Serial No. 508,913

3 Claims. (Cl. 129—43)

This invention has to do with improvements in record holders of the binder type adapted to be used in an upstanding position to contain removable files, the holder having sides which are expandable for normal active office use, and which are contractible and capable of being locked or latched together for storage of the holder.

More specifically, the invention relates to improvements in holders of this type in which the body comprises a pair of side plates hinged at their lower edges to a base which preferably is of U-shape and has upstanding ends at least partially closing the space between the side plates. The latter thus are capable of outward swinging expansion to enlarge their angular spacing for more convenient access in the handling of records in the holder. The body is supported by a pair of legs, each of which preferably is U-shaped to underlie the bottom of the holder when the sides are in collapsed position, the ends of the legs being pivotally connected to the upstanding ends of the holder bottom so as to be capable of outward swinging movement permitting the bottom of the holder to rest directly on a table surface. As generally characterized, these features of binder type holders are known in the art.

One of the principal objects of the present invention is to provide for adjustable variation of the side plate spacing and therefore capacity of the holder, in addition to mere mounting of the side plates for expansive and contractive movements about their hinges. In accordance with the invention, the holder bottom assembly is so constructed as to be expandable or contractible in the direction of the side plate spacing, thus enabling the holder to be widened or narrowed for the accommodation of greater or lesser record quantities. Also the invention contemplates providing, in conjunction with the expansive bottom assembly, a fastener or lock bridging across the upper edges of the side plates, and which is expandable and contractible in accordance with the adjustments made of the bottom structure.

Other objects of the invention have to do with the mounting of the legs in relation to the side plates and the upstanding ends of the holder bottom. Specifically contemplated in this respect is pivotal interconnection of each leg with a corresponding side plate so that the two swing together, and connections between the ends of the leg and the upstanding bottom plate ends in a manner such that each side plate and interconnected leg combination may be swung outwardly independently of the other side plate and leg.

All these as well as additional features and objects of the invention will be understood more fully from the following detailed description of an illustrative embodiment as shown by the accompanying drawing, in which:

Fig. 1 is a view showing the holder in perspective elevation;

Fig. 2 is an end view of Fig. 1;

Fig. 3 is a perspective view showing in fragmentary enlargement the relation of the bottom assembly and one leg and side plate in expanded position;

2

Fig. 4 is a cross-section on line 4—4 of Fig. 3; and Fig. 5 is a section taken through the lock strap on line 5—5 of Fig. 1.

The body of the holder may be regarded as comprising a pair of upstanding side plates 10 and 11, and a bottom plate assembly generally indicated at 12. The lower edges of the side plates have hinge connections at 13 with the bottom structure to hinge the side plates to swing between the contracted position of Fig. 1 to the outwardly inclined or expanded positions shown in Figs. 2 and 3. The bottom assembly 12 comprises a U-shaped sheet metal piece 14 having a horizontally extending base portion 14a, see Figs. 3 and 4, and integral upstanding end portions 14b. Referring to Fig. 4, a pair of plates 15 and 16 extending between and close to the spacing of the upstanding end portions 14b of the base, are placed flatly upon the bottom 14a and releasably retained thereon for transverse movement. Plate 16 may contain near both of its ends a transverse slot 17 aligned with a slot 18 in the base 14a, plate 15 carrying a bolt 19 extending through the slots and having a nut 20 which may be tightened against the underside of the base 14a. Plate 15 thus may be shifted within a range corresponding to the length of slot 18, and plate 16 similarly within a range corresponding to the length of slot 17. The lower edges of the side plates 10 and 11 are rolled at 21 to form a hinge section receiving respectively the rolled edges 22 of the plates 15 and 16. Thus the side plates may swing outwardly about the hinges so formed, and the bottom spacing of the side plates may be varied as desired within the range of adjustment afforded by the bolt 19 in relation to the slots 17 and 18.

The side plates may be held together at their upper edges by an appropriate latching or locking device, generally indicated at 23, shown typically as comprising a longitudinally adjustable strip 24 hinged at 25 to plate 11 and having at its opposite ends a side undercut head 26 receivable within a keeper T-slot 27 in plate 28 attached to side 10. As shown in Fig. 5, plate 28 is doubled over at the outside to accommodate a spring 29 against which the head 26 bears. The strap 24 is made in the form of longitudinally slideable sections 30 and 31, the former carrying a bolt 32 extending through slot 33 in section 31 so that the sections may be shifted to expand or contract the lock strap. Nut 34 of course holds the sections in adjusted position.

The holder body is supportable by a pair of U-shaped legs 35 having upstanding ends 36 pivotally connected at 37 to angle pieces 38 secured to the sides of plates 10 and 11. The upper ends of the legs have pin and slot connections at 38 with the upstanding ends 14b of the base plate, these connections typically being formed by pins 39 carried by the leg terminals and projecting through slots 40 in the offsets 41. As shown in Fig. 2, the pins 39 may have headed ends at the outside of the legs. Being pivotally connected to the side plates at 37, and having the pin and slot lost motion connections at 38 with the bottom ends 14b, the legs are shiftable at their pivot mountings with the side plates 10 and 11, as the spacing of the latter may be varied in accordance with adjustments made of the bottom slide plates 15 and 16. Hence, as the spacing between the lower edges of the side plates 10 and 11 is increased, the lower ends of the legs are swung out to correspondingly increase the spacing therebetween in accordance with the increased width of the holder.

When the holder assembly is in the condition shown in Fig. 1, the sides 10 and 11 may be substantially parallel and the legs 35 are swung inwardly to underlie the bottom assembly 12. Upon release of the lock at 23, the sides may be swung outwardly to the Fig. 2 and 3 positions to open the holder for normal office use. Out-

ward swinging of the side plates is accomplished by corresponding outward swinging of the legs so that the bottom 14a may rest directly upon a table surface. It is to be noted that each side plate and leg assembly is capable of outwardly swinging independently of the other side plate and leg, so that it may be moved outwardly and to such extent as may be desired, independently of the other.

I claim:

1. A record holder of the character described comprising: a generally U-shaped frame having an elongated base and upstanding end walls; a pair of side plates at opposite sides of said base; hinges connecting the lower edges of said plates with said opposite sides of said base so that each of said plates may be swung outwardly from a generally upright closed position to an outwardly inclined open position; means mounting each of said hinges on said base for lateral adjustment toward and away from each other to vary the spacing between said side plate lower edges and, consequently, vary the width of the holder; a pair of generally-upright supporting legs associated with each of said end walls; pivotal connections between the upper end of each leg and said wall and between an intermediate portion of each leg and the corresponding side plate, one of said pivotal connections having a generally-vertically-shiftable axis, whereby on outward swinging movement of a side plate the lower

5

ends of the legs connected thereto are swung laterally outwardly to serve as braces to prevent the holder from overturning when the said corresponding plate is in its open position, and whereby lateral outward adjustment of a side plate hinge swings the corresponding legs outwardly to compensate for the increased width of the holder.

2. The structure defined in claim 1 in which the connection between each leg and end wall includes a generally upright slot and pivot pin arrangement whereby the pivotal axis of said connection is shiftable vertically.

3. The structure defined in claim 1 in which the means mounting the hinges includes a pair of plates parallel to and in stacked relationship to the base and adjustable pin and slot connections between said plates and said base.
